UNITED STATES PATENT OFFICE.

EDWARD R. WHARTON, OF MEDFORD, MASSACHUSETTS, ASSIGNOR OF ONE-HALF TO
JOHN D. VERNER, OF MALDEN, MASSACHUSETTS.

BLADE DE-EDGING AND RECEIVING DEVICE.

Application filed July 13, 1927. Serial No. 205,521.

The object of this invention is to provide a device for dulling or de-edging discarded safety-razor blades after their keenness has been so impaired that they are no longer suitable for use in shaving, and to enable the de-edged blades to be conveniently segregated, so that they may be safely disposed of.

Discarded blades usually remain so sharp that they are a source of danger, if allowed to accumulate where they are liable to be picked up by children, and other more or less irresponsible persons.

The device in which my invention is embodied is adapted to be operated in such manner that a discarded blade is de-edged by a longitudinal movement thereof, and deposited by the same movement in a receptacle wherein it may be stored with other blades similarly treated, until the receptacle is filled, after which the accumulation of blades may be safely disposed of by another operation.

Of the accompanying drawings forming a part of this specification,—

Figure 1 is a side view of a de-edging and segregating device embodying the invention.

Figure 2 is a top plan view of the same, without the inner member hereinafter described of the segregating receptacle.

Figure 3 is an enlarged fragmentary section on line 3—3 of Figures 1 and 2.

Figure 4 is a section on line 4—4 of Figure 2, showing the inner member of the segregating receptacle.

Figure 5 is a fragmentary perspective view, showing the upper portion of said inner member.

The same reference characters indicate the same parts in all of the figures.

In the drawings, 12 designates a receptacle, preferably of sheet metal, having an open upper end which may be closed by a cover 13, hinged at 14 to one side of the receptacle, and provided with a flange 15, adapted to receive an ear 16 on the opposite side of the receptacle. Said ear may be perforated to engage a padlock, whereby the cover may be locked when closed. Fixed to an intermediate side of the receptacle 12, is a runway, composed, in this instance, of a bottom 17 and upstanding flanges 18, at opposite edges of the bottom. The runway may be supported by a bracket 19 fixed to the receptacle and the bottom of the runway. A safety-razor blade 20 is movable endwise on the runway, in a pre-

determined path, preferably by a pusher 55 composed of a base 21, and a handle 22, the base being provided with runners 23, movable in guiding slots 24 in the bottom 17. One of the runners is shown by Figure 4.

With the runway 1 associate de-edging 60 means, adapted to de-edge a blade while it is being moved in the runway and embodied in this instance, in file-surfaced blocks 25, fixed to the free ends of springs 26, the opposite ends of which are fixed at 27 to the runway 65 flanges 18. The blocks 25, are yieldingly supported by the springs in openings 28, in the flanges 18, and their serrated inner sides are adapted to bear simultaneously on the edges of the blade 20, when the latter is 70 moved in the runway toward the receptacle 12, the blade being de-edged by its movement between the file blocks. In other words, the edges are so reduced that they are deprived of dangerous sharpness. 75

The receptacle is provided with a receiving mouth 29, located in the path of the blade and arranged to receive the de-edged blade when it leaves the runway.

The blade receptacle preferably includes an 80 outer member provided by the receptacle 12 above described, and an inner member provided by a carton 30, removably inserted in the outer member, and provided with a slot 31, registering with the slot 29, the two slots 85 31 constituting a receiving mouth communicating with the inner member of the receptacle. When said inner member is filled, it may be removed and its slot 31 closed by a flap 32, which may be tucked behind a retaining 90 member 33 (Figure 5) formed by cutting parallel slits in one side of the inner member. The inner member thus charged and closed, may be disposed of in any suitable way. 95

The device is adapted for home use and for use in more or less public places, such as toilet rooms of sleeping-cars. Its use enables discarded blades to be conveniently and safely disposed of.

I am not limited to the de-edging members here shown, and the same may be of any suitable construction and material, whereby they are adapted to act as described.

The de-edged blades deprived of keen cutting edges, and therefore not dangerous to handle, would create an objectionable litter if allowed to lie about unsegregated. This

objection is avoided without loss of time by segregating the blades as fast as they are de-edged.

I claim:

- 5 1. A blade de-edger and receiver comprising a blade runway, formed to support a blade and guide it in a predetermined path, de-edging means associated with the runway and adapted to de-edge a blade while it is being moved in the runway, and a blade receptacle having a receiving mouth located in the path of the blade and formed to receive the blade when it leaves the runway.
- 10 2. A blade de-edger and receiver comprising a blade runway formed to support a blade and guide it in a predetermined path, a pair of de-edging members located at opposite sides of the runway and arranged to bear simultaneously on the edges of a two-edged blade while it is being moved in the runway, to de-edge the blade, and a blade receptacle having a receiving mouth located in the path of the blade and formed to receive the blade when it leaves the runway.
- 15 3. A blade de-edger and receiver comprising a blade runway formed to support a blade and guide it in a predetermined path, a pair of de-edging members located at opposite sides of the runway and arranged to bear simultaneously on the edges of a two-edged blade while it is being moved in the runway, to de-edge the blade, and a blade receptacle having a receiving mouth located in the path of the blade and formed to receive the blade when it leaves the runway, means being provided for pressing said members yieldingly against the blade edges.
- 20 4. A blade de-edger and receiver comprising a blade runway formed to support a blade and guide it in a predetermined path, de-

edging means associated with the runway and adapted to de-edge a blade while it is being moved in the runway, a blade receptacle having a receiving mouth located in the path of the blade and formed to receive the blade 45 when it leaves the runway, and a blade pusher guided by the runway and adapted to bear on the outer end of a blade therein.

5. A blade de-edger and receiver comprising a blade runway formed to support a blade 50 and guide it in a predetermined path, de-edging means associated with the runway and adapted to de-edge a blade while it is being moved in the runway, and a blade receptacle having a receiving mouth located 55 in the path of the blade and formed to receive the blade when it leaves the runway, said receptacle comprising an outer member fixed to the runway, and an inner member removably inserted in the outer member, the receiving mouth being provided by registering slots in the receptacle members, the inner member being provided with means for closing the slot therein, when said member is removed from the outer member. 65

6. A blade de-edger and receiver comprising a blade runway formed to support a blade and guide it in a predetermined path, de-edging means associated with the runway and adapted to de-edge a blade while it is being 70 moved in the runway, and a blade receptacle having a receiving mouth located in the path of the blade and formed to receive the blade when it leaves the runway, the receptacle being provided with a displaceable cover 75 adapted to be locked in closed position.

In testimony whereof I have affixed my signature.

EDWARD R. WHARTON.
